PREPARING AND PREMOLDING HEEL AND QUARTER PORTIONS OF BOOTS AND SHOES

Benjamin F. Hartwell, Leslie L. Hartwell, Jr., and Arthur F. Hartwell, Bellows Falls, Vt.

Application October 11, 1937, Serial No. 168,330

1 Claim. (Cl. 12—146)

Our present invention is directed to the improved method and process of preparing and premolding certain portions of boots and shoes, particularly the heel and quarter sections, and the object of the invention is to improve and perfect the methods of our prior and copending applications, Ser. Nos. 104,196, filed Oct. 6, 1936, and No. 137,708 filed April 19, 1937.

As explained in our said prior applications we have developed certain novel and improved methods of boot and shoe construction, wherein the premolding of the heel and quarter sections or other parts of the shoe, including the making of a lasted flange by the molding operation and conforming the entire heel and quarter sections into substantially final finished form prior to lasting, is an important characteristic; and our present invention is directed specifically to simplify the preparation of the heel and quarter materials, viz., the lining, the intermediate stiffening layer, and the outer finished upper material for the shoe quarter and heel portions, and preparing the same for the premolding operation.

While it is desirable to have a turned or finished edge when premolding shoe structures, we find that it is feasible to so form the sections and unite the same as to eliminate the edge-folding operation, thus greatly simplifying the manufacturing process for this particular shoe and the heel and quarter portions, as well as to improve the premolding operation which can be more readily preformed without danger of wrinkling or marring, with a minimum of thicknesses.

In carrying out our present invention therefor we specially prepare the blanks constituting the lining, intermediate stiffening layer, and outer finishing material, cutting or dieing out the same while all are flat, skiving the innermost stiffening layer, and uniting all three layers, as well as stitching the outermost edge, all while flat, and simultaneously trimming the lining layer, which is purposely made of larger area for this purpose, producing a serviceable finished edge as well as a heel and quarter section which will facilitate the premolding operation.

Referring to the drawing illustrating a preferred embodiment of our present invention,

Fig. 1 is a plan view partly in cross-section of the three prepared layers to constitute the heel and quarter sections of a boot or shoe;

Fig. 2 is a cross-sectional view;

Fig. 3 is a plan view illustrating the stitching and trimming;

Fig. 4 is a view in perspective on a reduced scale of the premolded quarter and heel sections, and

Fig. 5 is a cross sectional view on the line 5—5 of Fig. 4.

Referring to the drawing, 1 designates the outer finishing material constituting the shoe upper, 60 which is cut or dieed out while flat, and 2 indicates

the inner stiffening layer also cut or dieed of the same area and contour as that of the outer material 1, the layer 2 having a marginal beveled portion 3 entirely around its exterior contour. A lining layer of suitable material 5 is made of 5 larger area and contour than that of the other two layers, and all three may be notched as indicated at 6 and 7 for ready alignment when assembling as is usual. Suitable adhesive is supplied to each side of the stiffening layer 2 or to the inner surfaces of the outer finishing material 1 and the lining 5 which are to contact with the stiffening layer 2, or both if desired, and all three are then assembled while flat, as shown in Figs. 1 and 2.

Heat and pressure being applied to the three blanks thus assembled, the same are firmly united and thereupon the finishing and binding stitching 10 is applied, and simultaneously the surplus portion of the lining 5, as indicated at 12, is cut 20 therefrom, thus presenting a completely finished edge independently of any folding operation, as shown in Figs. 4 and 5.

The bevelled portion 3 of the stiffening material and the close cutting of the surplus lining presents an acceptable appearance to the edge of 25 the shoe, as the outer layer constituting the finish of the upper practically overlays the edge and predominates the appearance.

Thereupon the now prepared upper materials, 30 which have thus far been operated on while flat, are subjected to the molding operation, producing a finished contoured heel and quarter portion with the lasting flange 15 formed thereon, all as explained in our said prior applications. The 35 elimination of any folding operation on the uppermost or top edge of the three united layers eliminates the danger of wrinkles and greatly facilitates premolding.

We claim:

That improvement in the art of pre-molding a plurality of shoe upper materials into final finished form, with a finished edge along the top and an attaching flange along the bottom, independently of lasting operations, which consists 45 in cutting the outer shoe upper layer, a lining layer, and an intermediate stiffening layer into substantially uniform contour and area, thereupon uniting said layers with adhesive while flat, then simultaneously stitching and trimming the 50 top edge portions of said plurality of united shoe upper layers while still flat, and thereupon pre-molding the united and trimmed plurality of layers into final finished form, with an attaching flange inturned on the unstitched bottom edge, 55 said flange incorporating all three of said layers.
